Des. 192,834
Patented May 15, 1962

192,834

BAR OF SOAP OR THE LIKE

Robert Harry Clawson, Cincinnati, Ohio, and Willard Reeder Horne, Northvale, N.J., assignors to The Procter & Gamble Company, Cincinnati, Ohio, a corporation of Ohio

Filed Feb. 5, 1962, Ser. No. 68,668

Term of patent 14 years

(Cl. D73—1)

Fig. 1

Fig. 2

Fig. 3

Fig. 4

Fig. 5

Fig. 6

FIG. 1 is a top plan view of a bar of soap or the like showing our design.

FIG. 2 is an end elevational view of the same.

FIG. 3 is a side elevational view of the same.

FIG. 4 is a cross-sectional view taken on the line 4—4 of FIG. 3.

FIG. 5 is a cross-sectional view of the same taken on the line 5—5 of FIG. 1.

FIG. 6 is a perspective view of the same.

We claim:

The ornamental design for a bar of soap or the like, as shown.
